PACKAGE FOR NEEDLES OR THE LIKE

Karl-Heinz Deneke, auf dem Rott, Gressenich, near Aachen, Germany

Filed Oct. 1, 1965, Ser. No. 87,253

Term of patent 14 years

(Cl. D58—2)

FIGURE 4 is a plan view of the package for needles or the like in unfolded condition.

The dash lines in the drawing represent fold lines.

I claim:

The ornamental design for a package for needles or the like, as shown and described.
